UNITED STATES PATENT OFFICE.

JOHN MALCOLM NICOL, OF MILL VALLEY, CALIFORNIA.

PLOW AND JET-ELEVATOR DREDGE.

Application filed April 12, 1926. Serial No. 101,228.

My invention relates to the art of excavating under water, which is termed "dredging" and has as an object the providing of a combination of methods of excavating and elevating materials not hitherto used and that can be applied to both industrial dredging as used in civil engineering work and to mining dredging, that is, to the use of dredging appliances for the recovery of metals, minerals, 10 gems and by-products from alluviums, or what are commonly known as placers.

Present methods of dredging comprise the use of grab dredges, drag-line bucket dredges, dipper dredges, bucket dredges, and suction 15 dredges. Of these, the dipper dredge has perhaps the greatest excavating power, but the material is handled intermittently, the mechanism consisting essentially of a single bucket at the end of the dipper arm. The 20 dipper dredge is the only one in actual use that has a true shovel digging action, in that the mechanism admits of forcing the arm downward, while the cable pulls the dipper forward and into the material to be excavated. Conversely the arm can be forcibly 25 raised, so as to free the dipper when making a swing back for a new cut. In the present suction dredges there is a continuous action, but the lifting power is limited to the vacuum 30 created by the pump and this vacuum can easily be broken when the priming is lost. Furthermore, the ascending velocity in the suction pipe can rarely be maintained at or above fifteen feet per second, which will not 35 maintain heavy minerals in suspension.

My invention has as its principal object, the provision of a suction dredge operating with a powerful water jet that will raise heavy mineral particles and operate continuously 40 with a continuous vacuum. As a further object there is the provision of a combination of the aforesaid jet mechanism with an excavating member having a full shovel action, that is, having a swinging motion forward and back under full power control, and at the same time, a downward thrust and upward lift,—both under full power control. A further object is to devise, in relation to the 45 above mechanisms, a plow-shaped and plow- 50 action cutting shoe, fitted with protective grid openings to exclude the coarsest materials. These and other objects are accomplished in the following specification and drawings which describe the preferred embodiment of my invention.

In the drawings,—

Fig. 1 represents a side view or elevation of the main parts of the pontoon and dredge;

Fig. 2 represents a side view or elevation of the pontoon and dredge, showing the auxiliary grab buckets and stacker; 60

Fig. 3 is a plan view of Fig. 2;

Fig. 4 is an end view thereto;

Fig. 5 is an elevation, partly in section, of the trunnion assembly, viewing it from the 65 bow of the pontoon toward the stern;

Fig. 6 is a plan or top view of Fig. 5;

Fig. 7 is an end view of Fig. 5, looking toward the bow, that is, from the left end of Fig. 5; 70

Fig. 8 is a sectional elevation of the plow and jet mechanism;

Fig. 9 is a front elevation thereof;

Fig. 10 is a section of Fig. 8 on the line 10—10; and 75

Fig. 11 is a top or plan view of Fig. 8.

In said figures there is shown a main pontoon 1 floated in a prepared pond, this pontoon being provided with a vertical guide tower 2, forming at the same time a braced 80 gauntry to carry the sheaves for the cables and to act as a mast for the grab clamshell booms on either side. In this guide tower there is provided an upper fixed section 3 of a telescopic up-cast pipe and a lower section 4 connecting to a rotating elbow joined with one arm of the trunnion on the platform, to be described. This up-cast pipe delivers at its top 5 to a suitable material discharge which may lead to the metallurgical equipment or the regular discharge for a commercial dredge. Behind this up-cast pipe (as viewed in Fig. 1) is a down-cast pressure water telescoping pipe 6 which connects at its top to a pipe 7 receiving pressure water 95 from a centrifugal pump 8 which is driven by motor 9. These telescoping pipes are fastened to the vertically movable platform 10 sliding in vertical guides, such as 11, 12, by means of shoes 13. Below the movable platform is a trunnion on which swings the digging arm 14, containing within it the high pressure hydraulic supply down-cast pipe 15 and the up-cast pipe or hydraulic elevator 16. The pipe 16 is connected to a swinging elbow 17 mounted in a suitable bushing at 18, and connecting through another elbow 19 to the telescoping pipes 3 and 4 which deliver to the material discharge. The pressure water pipe 15 connects, through swing- 100 105 110

ing elbow 20 mounted in a suitable bushing 21, to elbow 22, which in turn connects to pipe 6, thus forming a trunnion for the water pipe 15. By means of these two trunnions the entire digging arm 14 beneath the platform can swing back and forth from any position in which the platform may be placed. The lower initial digging position of the arm 14 is shown in Fig. 1 and also the upper position near the end of the stroke when the platform is raised to the upper position, as shown at 23.

A main cable 24 operating over the braced boom 25, adjustable for height, pulls the digging arm forward and is operated by a main hoist 26, the cable passing over sheave wheel 27. The braced boom is provided with various swivel anchor points at the forward deck so as to have further adjustability for position. A back-pull cable 28 is provided to draw the digging arm back, and is operated by a suitable winch 29.

In Fig. 2 is shown a stacker 30 with associated operative mechanism, and spuds 31 for fixing the position of the pontoon, thereby enabling it to operate on a radius. A hydraulic cylinder and piston 32 operate by means of cables 33, the sheave wheels 34, which lower and raise the said platform 10. A grab bucket 35 which may be provided on either side of the pontoon, as shown in Fig. 3, is hoisted over a boom 36 and operated in the usual manner through cables 37, etc.

Housing 38 is shown in Figs. 2 and 4.

35 *Description of the plow and jet.*

In Figs. 8 to 11 the plow and jet are shown in detail. The plow 39 is a massive steel shoe having a shovel-shaped base at the front and a plow-shaped nose of steel 40. Grid openings 41 allow the finer material to pass into the interior of the plow but exclude the coarser minerals and rocks. The suction through the grid openings is created by the powerful water jet at the nozzle 42 which is bolted to a circular nozzle plate 43. The nozzle is supplied with pressure water from the pipe 15 through the bend 44. A constricted throat 45 properly positioned with respect to the nozzle 42 operates in conjunction with the powerful jet of water to create a vacuum within the casing (which is generally designated by 46). The cable 24 is attached to the plow at 47 in any suitable manner and the cable 28 is likewise attached at 48.

Operation.

The dredge having been floated in a prepared pond, the grab buckets can be used to dig a sufficiently deep hole to allow the digging arm to be lowered into cutting position. If work is done in digging a channel or harbor, the cutting plow need only be moved with relatively short strokes and at any required rate of advance, according as the material

has to be dug or "comes" to the suction. In placer mining for gold or stream tin, where digging against a bank of hard gravel, the digging arm can be swung through a full stroke, and if part of the gravel is above water level it can be brought up above the water and "break-down" bank, just as a steam shovel would do. On the return stroke the platform carrying the trunnion is raised, so as to allow of a free swing back and the "back-pull" cable 28 then comes into operation. When the digging arm arrives in vertical position the platform is lowered and a new cut started. The lowering of the platform and heavy mechanism provides a downward thrust so that the plow digs in at the beginning of the stroke. The hydraulic elevator 32 raises the platform 10 to the upper position 23 immediately preceding the back stroke of the arm 14 and thereupon releases the platform so that it may descend with suitable speed to dig in for the next stroke. The pontoon would be controlled as to position by spuds and side lines, just as in standard dredging operations, the advance being a side swing for each succeeding cut while working on a radius from one spud.

In this operation the hydraulic elevators do not lose their priming if exposed to air suction as in the case of centrifugal dredging pumps. Furthermore the up-cast pipe can be crowded to carry a far larger proportion of solids, even up to 20% or 30% and the ascending velocity can be maintained at 20' per second, as against the velocity of 12' to 15' in suction pumps.

The above-described mechanism has distinct advantages over those heretofore used. The excavating power is due to the pull of the cable, as in a regular dipper dredge, and to the downward or outward thrust of the digging arm, but as the shoe is shaped like a plow, its cutting and excavating power in heavy ground is much greater than in a dipper dredge. All material small enough to go through the grid openings is immediately sucked in and elevated in a continuous stream whereas any material too coarse is shoved to one side by the curved face of the plow and can be handled by the auxiliary grab or clamshell dredge. In former suction dredges excavation was effected by some form of auxiliary rotating head and the intake was caused only by the vacuum developed by a pump above water level. Any attempt to force the material to the suction in such devices might overload the power of the vacuum and cause the pump to lose its priming. Any attempt to attach the suction to a digging arm and bring the latter above the level would also cause loss of priming. In the present device the point of impelling energy is below water level and as close to the actual intake as possible. The exterior velocity of intake is thus equal to the pressure of the atmosphere plus

the head of water due to depth of immersion of the digging member, and is accentuated by the forcible shovel action of the shoe. The ascensional velocity may be maintained at 5 20' per second,—a condition that would be impossible in a centrifugal pump. With this jet elevator gold and other heavy minerals can be maintained in suspension and carried upward, and the suction can be choke-fed 10 with fines without loss of priming.

There is thus provided a combination of a powerful vacuum, adjacent the intake of a water jet, with a digging member having a powerful action and swinging through a full 15 stroke. In addition this combination is supplemented by the powerful downthrust, enabling the digging member to dig in, and also the special construction of the digging member or plow, which enables it to go through 20 heavy and mixed ground. These and other advantages pertaining to the present invention reside not only in the specific features shown, but in the general combination of a 25 hydraulic jet within a powerful digging cutting member.

As many apparently widely different embodiments of this invention may be made without departing from the spirit thereof, it is understood that I do not intend to limit 30 myself to the specific embodiment above described, except as indicated in the appended claims.

I claim:—

1. In a pontoon dredge, the combination of 35 a digging arm whose upper end is mounted on a trunnion that is suspended from a ver-

tically movable platform, power means for raising and lowering said platform, a hydraulic jet elevator in said digging arm for elevating excavated material, and telescoping 40 conduits, respectively supplying said jet with pressure water, and conveying away excavated material.

2. In a pontoon dredge, the combination of 45 a power-controlled movable digging member with a hydraulic jet elevator, said digging member being equipped with a hollow plow-shaped shoe piece at its lower end, with a double-headed hollow trunnion piece at its upper end, two connecting pipes within the 50 arm, one pipe being for the supply of pressure water to the jet, and the other for the upraise of the dredged material, these pipes being connected respectively at their upper ends to the respective arms of the trunnions 55 and at their lower ends to the shoe piece.

3. In a pontoon dredge, the combination of 60 a rigid digging arm, a heavy shoe at the end thereof having a plow-shaped forward cutting edge and openings adjacent thereto, a vertically movable platform supporting 65 said arm on trunnions, a hydraulic jet elevator in the arm having its suction opening near said openings in the shoe, means for swinging the arm and raising and lowering the platform, a conduit supplying to said jet elevator pressure water, and a conduit for conveying away the excavated materials.

In testimony that I claim the foregoing, I have hereunto set my hand this 8th day of 70 March, 1926.

JOHN MALCOLM NICOL.
